UNITED STATES PATENT OFFICE.

FRANK JARVIS, OF HAUPPAUGE, NEW YORK.

ATTACHMENT FOR STIRRUPS.

1,160,082.

Specification of Letters Patent. Patented Nov. 9, 1915.

Application filed October 18, 1913. Serial No. 795,984.

To all whom it may concern:

Be it known that I, FRANK JARVIS, a citizen of the United States, residing at Hauppauge, in the county of Suffolk and State of New York, have invented certain new and useful Improvements in Attachments for Stirrups, of which the following is a specification.

This invention relates to stirrup attachments and has for its primary object to associate with the stirrup suitable means for preventing the slipping of the foot therein, after the tread portion of the stirrup has become worn and consequently smooth due to constant use.

Another object of this invention is to provide a device simple of construction and inexpensive to manufacture, the device comprising a suitable plate with which is connected elastic means so as to yieldingly engage the plate with an ordinary type of stirrup now in use, and at the same time will allow for the ready removal of the same therefrom when it is so desired.

Other objects as well as the nature, characteristic features and scope of my invention will be more readily understood from the following description taken in connection with the accompanying drawings and pointed out in the claims forming a part of this specification.

Referring to the drawings:—Figure 1 is a side elevation of a stirrup illustrating the application of my invention, a portion thereof being shown in section to disclose details; Fig. 2 is a cross sectional view taken on the line 2—2 of Fig. 1 and looking at the top of my improved anti-slipping plate; Fig. 3 is a sectional view taken on the line 3—3 of Fig. 2; and Fig. 4 is a perspective view of a variant form of my improved plate.

In the drawings wherein is illustrated the preferred embodiment of this invention an ordinary stirrup 5 is provided which is made of wood, metal or any other suitable material and is provided with an ordinary tread portion 6 which has formed therein an elongated longitudinally extending recess 7.

My improved anti-slipping plate in the present instance comprises a pair of metal straps 8. Each of the straps 8 has a portion of one of the longitudinal edges thereof turned at right-angles to the body thereof and thence into parallelism with the body

as indicated at 9. The opposite ends of each of the plates 8 are curved inwardly conforming to the configuration of the tread plate 6 of the stirrup, the upper face of each of said plates being serrated or roughened as at 10. A portion of each of the plates 8 beneath the serrated or roughened portion 10 thereof is engaged with the upper face of the tread plate 6 of the stirrup 5 on the one side of the recess 7 thereof, while the flanges 9 are engaged with the lower face of the tread plate 6 as advantageously illustrated in Fig. 3.

In order to retain the plates 8 in engagement with the tread plate 6 of the stirrup 5, suitable resilient means 11 are provided which in the present instance comprise a plurality of springs each of which is formed from a single strand of wire, having the one end of each engaged with one of the plates 8 while the opposite end of each is engaged with the opposite plate, an intermediate portion of each of said wires being helically wound as indicated at 12 so as to normally retain the plates 8 in engagement with the portions of the tread plate 6 of the stirrup.

In Fig. 4 wherein is shown a variant form of my improved device, a sheet metal plate 13 is provided which has the opposite ends thereof flexed so as to provide parallel arms 14, each of which has a flange 15 formed thereon which is provided by turning one of the longitudinal edges thereof upwardly into right-angled relation with the body, the opposite longitudinal edge of each of said arms has formed thereon elongated tread plates 16 which preferably extend beyond the ends of said arms and have the upper faces thereof roughened or serrated as indicated at 17. The one end of each of said arms 14 being connected through the medium of a curved strap 18, said strap being provided by flexing the opposite ends thereof, as above pointed out, said plate being made of a suitable resilient metal, in order that the flanges 15 and plates 16, which extend in parallel relation to each other, will be snugly engaged with the upper and lower faces of the tread plate 6 of the stirrup.

The arms 14 are snugly engaged with the plate 6, in view of the fact that the plate in this instance is made of a suitable spring metal, the arms 14 thereof being provided by flexing the opposite ends of the strap 13 as above pointed out, thereby causing the

strap to be normally under tension while the arms 14 are arranged in parallel relation as shown to advantage in Fig. 4.

In the operation of the device as illustrated in Figs. 1, 2 and three of the drawings, the straps 8 are pressed inwardly so as to compress the springs 11, and said plates then engaged in the recess 7, the flanges 9 and the body portion of each of said straps being engaged with the lower and upper faces respectively of said tread plate 6, and pressure released therefrom, thereby allowing the springs 11 to expand causing each of the plates 8 to be snugly engaged with the portion of the tread plate 6 as illustrated to advantage in Fig. 3.

In using the form as illustrated in Fig. 4, the free ends of the arms 14 are flexed inwardly and the device inserted in the recess 7, the flanges 15 of the arms engaging with the lower face of the tread plate 6 of the stirrup while the elongated plates 16 engage with the upper face thereof. As soon as pressure is released from the free ends of the arms it is obvious that the same will expand outwardly due to the resiliency of the metal, causing a positive engagement of the device with the tread plate 6.

It will be understood that the above description and accompanying drawings comprehend only the general and preferred embodiment of my invention and that various minor changes in details of construction, proportion and arrangement of the parts may be made within the scope of the appended claims and without sacrificing any of the advantages of my invention.

Having thus fully described my invention what I claim as new and desire to secure by Letters Patent is:—

1. An anti-slipping attachment for stir-

ups, including, in combination with a stirrup having a slotted tread, expandable and contractible members for engagement in said slot, whereby said members may be engaged with the stirrups when placed in said slots, and the attachment held from accidental displacement.

2. In combination with a stirrup, a stirrup attachment, including a pair of straps carried by said stirrup, and a plurality of springs associated with said straps for yieldingly engaging the latter with said stirrup.

3. In combination with a stirrup, a stirrup attachment, including a pair of straps each of which conforms to the configuration of said stirrup, and a plurality of springs interposed between said straps for yieldingly engaging the latter with said stirrup.

4. In combination with a stirrup, a stirrup attachment, including a tread plate provided with an elongated longitudinally extending slot, a pair of straps each of which has a portion of one of the longitudinal edges thereof turned into parallelism with the body thereof for engagement beneath said tread plate, the body portion of each of said straps engaging with the upper face of said tread plate, and a plurality of elastic elements interposed between said straps and lying in the slot of said tread plate for detachably engaging said straps with said tread plate, each of said elements comprising a single strand of wire the opposite ends of which are engaged with said straps.

In testimony whereof I affix my signature in presence of two witnesses.

FRANK JARVIS.
